(57) **CLAIM**

The ornamental design for a jaw tip, as shown and described.

DESCRIPTION

FIG. 1 is a top perspective view of a jaw tip attached to a jaw of our new design;
FIG. 2 is a bottom perspective view thereof;
FIG. 3 is a top plan view thereof;
FIG. 4 is a bottom plan view thereof;
FIG. 5 is a left side view thereof;

FIG. 6 is a right side view thereof;
FIG. 7 is a front elevation view thereof; and,
FIG. 8 is a rear elevation view thereof.
The broken lines shown in the drawings illustrate portions of the jaw tip that forms no part of the claimed invention.
